UNITED STATES PATENT OFFICE

1,996,174

HYDRAULIC PRESS FOR MOLDING AND DRYING STEREOYPE MATRICES

Karl Schäflein, Berne, Switzerland

Application March 31, 1933, Serial No. 663,708
In Germany April 15, 1932

2 Claims. (Cl. 101—12)

The invention relates to a hydraulic press for molding and drying stereotype matrices and having a movable press head, the characteristic feature being that the press head is lowered for molding by hydraulic pressure on one end surface of the piston and is then relieved from the hydraulic pressure, so that the drying of the molded matrices takes place in the molding press under the weight of the press head and of the parts connected with same.

In the known hydraulic matrix molding presses the lower press platen is raised by hydraulic pressure against a stationary press head. After the molding the pressure is reduced in order to dry the molded matrices under reduced pressure, but there is nothing to prevent the press platen from sinking further and entirely relieving the pressure.

This drawback is overcome by the invention. On the drawing one construction of a hydraulic press is shown.

Fig. 1 being a section through the longitudinal middle of the press, and

Fig. 2, a cross section.

The press head *a* is connected by side ties *b* with the cross piece *c*, on which the piston *e* working in the cylinder *d* is fastened. The cylinder *d* is in the press platen *f*. A pump *g* forces liquid out of the tank *h* through pipes *i*, *k* into the cylinder *d* at the top and bottom, from which it flows back through the pipes *l*, *m*, into the tank *h*. The control of the valves takes place in the way usual in such presses.

In order to raise the press head when starting to work, liquid is forced by the pump *g* through the pipe *k* into the annular space below the piston *e*. After the form together with the matrix and packing has been pushed under the form, the press head *a* is lowered by conducting liquid to the upper end of the cylinder through the pipe *i*. As soon as the molding has taken place, the pres-

sure can be relieved by leading the liquid away from the upper end of the cylinder *d*, so that the weight of the press head *a*, together with the side ties *b*, and the cross piece *c*, will alone act on the matrix during the drying. For drying the matrix the press platens are heated in known manner, for example by electricity or steam.

What I claim and desire to secure by Letters Patent of the United States is:—

1. In a hydraulic press for molding and drying stereotype matrices, the combination of a movable press head, side ties attached to said press head to guide the latter in the press frame, a cross piece connecting the lower end of said ties, a piston connected with said cross piece and having

two end surfaces, a stationary press platen, a cylinder therein for said piston, means for applying hydraulic pressure to one of said surfaces for the purpose of raising said press head, and means for applying hydraulic pressure to the other one of said surfaces for the purpose of lowering said press head to thereby mold a matrix.

2. In a hydraulic press for molding and drying stereotype matrices, the combination of a movable press head, side ties attached to said press head to guide the latter in the press frame, a cross piece connecting the lower end of said ties, a piston connected with said cross piece and having

two end surfaces, a stationary press platen, a cylinder therein for said piston, means for applying hydraulic pressure to one of said surfaces for the purpose of raising said press head, and means for applying hydraulic pressure to the other one of said surfaces for the purpose of lowering said press head to thereby mold a matrix, the hydraulic pressure being released after molding of the matrix so that the drying of the molded matrix takes place only under the weight of said head and associated parts.

KARL SCHÄFLEIN.
